UNITED STATES PATENT OFFICE.

DAVID D. GORDON, OF CHICAGO, ILLINOIS, ASSIGNOR TO THE YOST ELECTRIC MANUFACTURING COMPANY, OF TOLEDO, OHIO, A CORPORATION OF OHIO.

SWITCHING DEVICE.

1,184,678.

Specification of Letters Patent. Patented May 23, 1916.

Application filed October 26, 1914. Serial No. 863,648.

To all whom it may concern:

Be it known that I, DAVID D. GORDON, a citizen of the United States, residing at Chicago, in the county of Cook and State of Illinois, have invented a certain new and useful Improvement in Switching Devices, of which the following is a full, clear, concise, and exact description, reference being had to the accompanying drawings, forming

10 a part of this specification.

My invention relates to switching devices and has for its object the provision of a switch element alternately operable from a circuit closing to a circuit opening position 15 which is controlled by a single actuation thereof. In accordance my improved device may be of particular benefit in connection with pull sockets where a single actuating member is employed or may be used in other 20 switching devices where a single member, for instance a reciprocating member, may be used alternately to effect circuit closure or circuit opening.

More particularly my invention is an improvement over the device set forth in my co-pending application Serial No. 818,237, filed Feb. 12, 1914.

In one of the preferred forms of my invention, I utilize a pawl and ratchet mechanism of such a character that the ratchet may carry the contact element and this ratchet is moved throughout a part of its movement by a pawl under the actuation of a control member, the remaining movement of the 35 ratchet being automatic to complete a snap action circuit rupture or circuit closure.

I will describe this preferred form with various modifications in the accompanying drawings, in which—

40 Figure 1 is a side view partly in section of my improved switch mechanism; Fig. 2 is a view on line *a—a* of Fig. 1; Fig. 3 is a view similar to Fig. 2 showing the parts in an alternative position; Fig. 4 is a view similar 45 to Fig. 1 but at right angles thereto; Fig. 5 is a plan view partly in section of a modified form of the device; Fig. 6 is a view on line *b—b* of Fig. 5; Fig. 7 is a plan view partly in section of a further modification, and Fig. 50 8 is a view on lines *c—c* of Fig. 7.

My improved structure as illustrated more particularly in Figs. 1, 2, 3 and 4 comprises a socket having a supporting element 1 of insulating material within which all of the apparatus is mounted. One lead in wire 2

has its circuit carried downwardly by a conducting bolt 3 directly to the central contact 4 of the socket and the other lead in wire 5 has the continuance of its circuit toward the outer contact 6 of the socket controlled by 60 the switching device which forms the subject matter of my invention. This switching device is adapted to complete the circuit between a stationary switch plate 7 and a second stationary switch plate 8, both having 65 yielding extensions such as 9 to effect a more thorough contact. The element 8 is directly connected with the conductor 5 and the element 7 is directly connected with the exterior contact 6. The circuit through 70 these elements 7 and 8 is completed by a rotatable switch element having the contact arms 10 and 11 which are electrically connected together, and with the metallic strip 12. The movable switch element consisting 75 of the parts 10, 11 and 12 is pivotally mounted by having extensions 13 and preferably has a coat of insulation 14 about which a metallic ring 15 may preferably be placed to be engaged by an operating pawl as will 80 presently appear, the insulating coat 14 serving to insulate the contact device 10, 11 and 12 from the operating portion of the switch. The metallic envelop 15 has a groove 16 which coöperates with the free extremity 17 85 of a coiled spring 18, which coiled spring is mounted about a pin 19. An operating arm 20 is also pivotally mounted upon the pin 19 and is held in its outermost position shown in Fig. 2 by the opposite free extremity 21 90 of the spring 18. This pivotally mounted arm 20 consisting preferably of two parallel legs carry at its free extremity a pivotally mounted pawl 22. This pivotally mounted pawl has a finger 23 adapted to engage the 95 rotatable contact element and also has a guard finger 24 which impinges against the outer surface of the ratchet element of which the envelop 15 forms part. The pawl 22 as stated is pivotally supported by the arm 20 100 and has a hooked extremity 25 adapted to receive the ball 26 forming the extremity of the operating member 27. This operating member passes through an orifice 28 and may be suitably actuated by a chain 29. This 105 particular curved operating member 27 forms the subject matter of my co-pending application Serial No. 818,238, filed Feb. 12, 1914. Each pull exerted by the operating member 27 (Fig. 2) rotates the arm 20 in a 110

clockwise direction so that the pawl 22 rotates the ratchet element or moving contact also in a clockwise direction.

It will be seen that the initial pull of the member 27 rotates the pawl 22 itself about its pivotal contact should said pawl be away from the ratchet element and the guard finger 24 limits this rotation so that the pawl assumes its proper position with the

16 finger 23 pushing against the adjacent extremity of the ratchet. Assuming now that the pull is being exerted by the operating member 27 to rotate the arm 20, then the ratchet element is rotated into the dotted

15 position as shown in Fig. 3 whereupon by a slight further actuation of said operating member the ratchet element passes its critical position and its further clockwise rotation is completed by the arm 17 of the

20 spring 18 so that the element finally comes to rest in the position shown in Fig. 3 which is the position alternative to that of Fig. 2.

A second actuation of the control member 27 passing through a like sequence of move-

25 ments again brings the ratchet element to the position of Fig. 2. It will be seen that a portion of the movement of this contact element 10, 11 and 12 is brought about by the control member 27 and after it has been

30 moved beyond its critical position the spring 17 completes the movement by snap action into its other limiting position. It will be seen that the contact springs 9 have a very extended length so that the elements

35 10 and 11 will not leave the said elements 9 (when moving the switch from circuit closure to circuit rupture) until after the ratchet element has passed its critical position and is moving by snap action under the

40 influence of the spring 17.

The simplicity of this structure will be readily apparent from what has been de-

45 scribed. There are three rotatable elements and one operating spring and these four elements provide a device operable through the agency of one control member to get both a quick-make and quick-break or what might be termed a snap action circuit rup-

50 ture and snap action circuit closure.

55 In Figs. 5 and 6, I show a modified form of structure in which the pawl 22^a engages the ratchet element 12 upon the side nearest to the arm 20. The control element 27^a is placed between the pawl 22 and the arms 20

60 and engages the hooked extremity 25^a in a manner to again throw the guard finger 24 against the ratchet element. In this structure the ratchet element rotates in a direction opposite to that of the arms 20.

65 In Figs. 7 and 8, I have a structure some-what similar except that I use a recipro-

cating slide 30 having the finger knob 31 to control the switch element. This element

70 consisting of the parts 10^b, 11^b and 12^b is similar to the switch element shown in the

other figures and co-operates with spring fingers 9^b, 9^c. The pawl 32 is pivotally mounted upon the slide 30 and engages the nearest extremity of the ratchet element similar to the structure shown in the other 70 figures. A single spring 33 has one free extremity 34 engaging the ratchet element and the other free extremity 35 engaging a pin 36 which tends to press the pawl 32 against the ratchet element 12^b. The spring 75 thus again controls the action of the pawl against the ratchet element and also simultaneously controls the ratchet element. The contact springs 9^b are again made long enough so that no circuit rupture takes 80 place until the snap action movement of the combined contact ratchet element.

From what has been described the nature of my invention will be clear to those skilled in the art, and it will also be clear that 85 modifications may be made without departing from its spirit.

Having however thus described various forms of carrying out my invention, what I claim as new and desire to secure by Letters Patent is:

1. A pull socket movement comprising a flexible tension member, a pivoted arm movable by said tension member, a stationary switch element, a movable switch element 95 co-operating therewith, a rotatable plate carrying said movable switch element, a pawl carried by said pivoted arm and adapted to engage said plate, and a spring interposed between said pivoted arm and said plate, said pawl when actuated by the movement of said pivoted arm rotating said plate against the action of said spring to and beyond its position of repose and said spring completing the forward movement 100 of said plate to its alternative position.

2. A pull socket movement comprising a flexible tension member, a pivoted arm movable by said tension member, a stationary switch element, a movable switch element 110 co-operating therewith, a rotatable plate carrying said movable switch element, a pawl carried by said pivoted arm and adapted to engage said plate, and a compression spring 115 engaging both said pivoted arm and said plate, the plate engaging an extension of said spring being parallel to said plate when said plate is in one or the other of its resting positions and normally holding said plate in said resting position, said pawl when actuated by the movement of said pivoted arm to rotate said plate against the action of said spring to and beyond its position of repose.

3. A pull socket movement comprising a 125 flexible tension member, a pivoted arm movable by said tension member, a stationary switch element, a movable switch element co-operating therewith, a rotatable plate carrying said movable switch element,

a pawl carried by said pivoted arm and adapted to engage said plate, and a spring interposed between said plate and said pivoted arm, said pawl being pivotally mounted upon said pivoted element, and said tension member engaging said pawl so as to rotate said pawl against said plate.

In witness whereof, I hereunto subscribe my name this 22nd day of October, A. D., 1914.

DAVID D. GORDON.
